(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevation view of a first embodiment of a display screen or portion thereof with graphical user interface, showing our new design;

FIG. 2 is a front elevation view of a second embodiment of a display screen or portion thereof with graphical user interface, showing our new design;

FIG. 3 is a front elevation view of a third embodiment of a display screen or portion thereof with graphical user interface, showing our new design;

FIG. 4 is a front elevation view of a fourth embodiment of a display screen or portion thereof with graphical user interface, showing our new design; and,

FIG. 5 is a front elevation view of a fifth embodiment of a display screen or portion thereof with graphical user interface, showing our new design.

The product of FIG. 1 is display screen or portion thereof with graphical user interface. The figure is impression drawing.
